UNITED STATES PATENT OFFICE.

CHARLES A. GREEN AND HAROLD J. BRUNK, OF CHICAGO, ILLINOIS, ASSIGNEES TO
C. F. PEASE COMPANY, A CORPORATION OF ILLINOIS.

ARC LAMP.

Application filed April 11, 1924. Serial No. 705,771.

This invention relates to improvements in electric arc lamps such as used in the blue printing, photo engraving and other arts, and more particularly to a globe holder for 5 such lamps.

In arc lamps of the type described, the globe is supported between top and bottom holders, one of which, usually the bottom holder, is normally fixed, but adjustable to 10 permit of the globe being positioned and removed. Both holders are generally carried by a common frame member. In practice, these lamps are used singly for certain kinds of work, but for other kinds of work 15 a battery of lamps, grouped rather closely, is used. In each instance the temperature rises to quite a high degree and especially is this true when the lamps are used in battery formation where each is not only 20 subject to its own heat, but also to the heat developed by the adjacent lamps.

The arc lamps are grouped closer together in blue printing than in other arts, which increases their temperature, in addition to 25 the fact that more current is used per lamp than under normal conditions. They are especially so designed in order to give a better color value to the light with the arcs at high temperatures. The high temperatures cause expansion, which is greater in the globe than in the member which carries the holders and in consequence the hot globe 30 bulges out of shape. Upon subsequent contraction therefore, the seal between the globe and the holders is disturbed and leakage of air into the globe occurs resulting in wasteful consumption of carbon and bowing of the arc to one side causing localized heating of the glass and breakage, necessitating frequent renewals and materially increasing the 35 cost of operation.

The present invention contemplates the provision of a resilient or yielding holder for the globe which will effectively maintain the seal at both ends thereof at all 40 times through the action of upward pressure of a spring member, thus preventing breakage, such as above described.

Other objects and advantages of the invention will be apparent from the following description taken in connection with the accompanying drawings, wherein one form 45 of the invention is illustrated.

In the drawings:

Fig. 1 is a front elevation of a battery of

arc lamps as used in the blue printing art, for instance.

Fig. 2 is a longitudinal sectional view of a holder constructed in accordance with the present invention.

Fig. 3 is a top plan view thereof.

In Fig. 1 the arc lamps 10 are arranged in a group as used in blue printing machines and are shown mounted on a transverse pipe or conduit 11, said lamps comprising the carbons 12 and 13, the controlling and feeding mechanism 14, globe 15 and reflector 16. The globe is confined between top and bottom holders 17 and 18, respectively. These 60 holders are usually carried by a common frame, not shown in the drawings.

According to the present invention, the lower globe holder is made yieldable so as to maintain an air tight seal at the top and bottom of the globe at all times despite dimensional variations therein occasioned by 70 changes in temperature. To this end the holder 18 is in the form of a plug-like member flared outwardly at its upper end, as at 19, and screw-threaded at its lower end, as 80 at 20, for engagement with a suitable screw-threaded aperture in the lower supporting leg of the frame member, not shown, which carries both holders. This plug-like member is provided with a central opening 21 85 extending therethrough which accommodates the lower carbon 13. At its lower end opening 21 is flared outwardly and screw-threaded, at 22, for receiving the lower carbon holder 23. An annular chamber 24 90 is provided in the upper end of the plug-like support 18 and an inner tube 25 is provided which forms a wall common to both chamber 24 and the central opening 21. The chamber 24 extends below the outwardly 95 flared portion 19 of the support, providing a downward extension of the chamber in the form of an annular groove 26. A movable supporting plate 27, centrally apertured to permit of the inner tube 25 projecting 100 therethrough, is mounted in the chamber 24 and is accurately machined around its inner and outer peripheries for snug engagement with the inner tube 25 and the outer wall of chamber 24, respectively. A coiled spring 105 28 seats down into annular groove 26 at its lower end and engages upwardly against the under face of plate 27 at its upper end. Thus the plate floats on the spring and if 110 the ends of the globe are not entirely square

the plate is free to tilt slightly and thus effect a sealing of the ends of the globe just as efficiently as in cases where a perfect globe is encountered. In order to permit this tilting of the plate despite the snug fit thereof in chamber 24, the inner periphery thereof is reduced or beveled, as at 27^a, and the outer periphery is rounded, as at 27^b. Lateral retaining lugs 29 are pressed outwardly from the upper edge of the inner tube 25 to prevent displacement of plate 27, and also to limit its upward travel.

In practice, the holder 18 is first screwed into engagement with the screw-threaded opening provided in the lower end of the common member which carries both globe holders, the globe is then moved into engagement with the top holder 17 and then the lower end of the globe is swung into position over the holder 18, the latter being then adjusted upwardly until plate 27 has been brought into firm engagement with the lower edge of the globe. To facilitate adjusting the holder 18 the same is knurled, as at 29.

25 It will be obvious from the foregoing that plate 27 upon which the globe rests when in position will be held in sealing engagement with said globe by the spring 28 at all times, despite dimensional variations occasioned by changes in temperature and that said spring will also function to maintain a similar engagement between the upper end of the globe and top holder 17. The plate 27, as previously described, is accurately machined 30 around its inner and outer peripheries so as to snugly fit the walls of chamber 24 to thus minimize leakage of air into the globe between plate 27 and the inner tube 25. When it is desired to remove the globe for any 40 reason, the support 18 is screwed down until the lower end of the globe will clear said support after which it is swung to one side and removed.

45 It will be obvious to those skilled in the art that the invention is susceptible of various changes and modifications, and accordingly it is not desired to limit or restrict the same to the particular form or arrangement of parts herein illustrated except where limitations appear in the appended claims.

What we claim is:—

50 1. A globe holder for arc lamps comprising a plug-like member having a central opening therethrough, and a chamber in its upper end, an inner tube providing a wall common to both the opening and the chamber, a plate in said chamber provided with an opening through which said tube projects, and resilient means interposed between said plate and the bottom of said chamber.

55 2. A globe holder for arc lamps comprising a plug-like member having a central opening therethrough a carbon holder closing the lower end of said opening and a chamber in its upper end, an inner tube pro-

viding a wall common to both the opening and the chamber, a plate in said chamber provided with an opening through which said tube projects, resilient means interposed between said plate and the bottom of said chamber, and means for limiting the upward movement of said plate. 70

3. A globe holder for arc lamps comprising a plug-like member having a central opening therethrough and a chamber in its upper end, an inner tube providing a wall common to both the opening and the chamber, a plate in said chamber provided with an opening through which the tube projects, resilient means interposed between said plate and the bottom of said chamber, and means for limiting the upward movement of said plate, said means being in the form of laterally projecting lugs carried at the upper end of said tube. 80

4. A globe holder for arc lamps comprising a plug-like member having a chamber in its upper end, a plate in said chamber fitting the same snugly to form a sliding contact permitting substantially no leakage of air 90 therethrough, resilient means interposed between said plate and the bottom of said chamber, and means for limiting the upward movement of said plate. 95

5. A globe holder for arc lamps comprising a member having a screw threaded extension, an annular recess in the other end thereof, an extension of said recess forming a seat for a spring, a helical spring on said seat, and a ring having a sliding seat in said 100 annular recess, said ring resting on said spring and forming a yielding seat for said globe.

6. A globe holder for arc lamps comprising a member having a screw threaded extension, an annular recess in the other end thereof, an extension of said recess forming a seat for a spring, a helical spring on said seat, a ring having a sliding seat in said 110 annular recess, said ring resting on said spring and forming a yielding seat for said globe and being beveled at its inner edge and rounded at its outer edges to permit tilting thereof, without permitting substantial leakage of air past said edges into said globe. 115

7. A globe holder for arc lamps comprising a plug-like member having a central opening therethrough, and a chamber in its upper end, an inner tube providing a wall common to both the opening and the chamber, a plate in said chamber provided with an opening through which said tube projects, resilient means interposed between said plate and the bottom of said chamber, and a removable carbon holder held in the lower end 120 of said tube. 125

In testimony whereof, we have subscribed our names.
